SPECIALTY COMPANY, OF NEW ORLEANS, LOUISIANA, A CORPORATION OF
LOUISIANA.

SANITARY-DRINKING-CUP PACKAGE.

1,101,107.

Specification of Letters Patent. Patented June 23, 1914.

Application filed January 21, 1913. Serial No. 743,381.

To all whom it may concern:

Be it known that I, JULIUS D. TSCHOPIK, a citizen of the United States, and resident of New Orleans, in the parish of Orleans and State of Louisiana, have invented certain new and useful Improvements in Sanitary-Drinking-Cup Packages; and I do hereby declare the following to be a full, clear, and exact description of the same, reference 10 being had to the accompanying drawings, forming part of this specification, and to the figures and letters of reference marked thereon.

This invention relates to improvements in packages for containing sanitary drinking cups made of paper or other suitable material, which are designed to be discarded after use.

The invention has for its object to provide 20 a package or holder in which a number of superposed cups in collapsed or flattened form may be conveniently carried by the user and a single cup removed from the packet without disturbing the others.

To these ends the invention consists in certain novel details of construction and combinations and arrangements of parts all as will be now described and the particular 25 features of novelty pointed out in the appended claims.

In the accompanying drawings, wherein is illustrated the preferred embodiment of the invention,—Figure 1 is a perspective view of a package embodying the present 30 invention, the casing or binder being shown open. Fig. 2 is a longitudinal sectional view with the casing closed. Fig. 3 is a detail view of one of the drinking cups.

Similar letters of reference in the several 40 figures indicate the same parts.

Referring to the drawings, the casing or holder for the cups is formed of a single piece of suitable material such as paper, and folded to form a backing or base A, a relatively long flap a, and a short flap a', beneath which the end of flap a is adapted to be held when the packet is closed. The drinking cups or receptacles B in the present instance are preferably made of paper, 45 and of any suitable form which will permit the cups to be flattened or collapsed, so that they may be placed within the casing or holder, the preferred form of the cups being that of an ordinary paper bag, as shown. 50

A suitable number of superposed cups are

placed in the casing with their open ends beneath the short flap a', being held in place by suitable fastening means such as C, although any other well known fastening means may be employed. These fastening means, it will be noted, pass through the cups below the open ends thereof, and effectually close the ends, thus keeping the interior of the cups clean and sanitary, until 60 ready for use.

Below the fastening means each cup is provided with a line of weakness, such for example, as the line of perforations c⁶ extending in a straight line across the cup through both walls. By such means a single 70 cup may be separated from the pack as desired, without disturbing the remaining cups in the pack, the walls of individual cups being of the same height, as will be readily understood.

From the above description it will be seen that the pack of cups is protected by the casing and the whole is in a convenient form to be carried on the person of the user. Moreover, a cup can be readily separated 75 from the pack when needed, and having a straight tearing line, the top edge or brim of the cup will be left unbroken permitting the cup to be filled up to the top, and preventing the spilling of the contents when 80 drinking and the walls of individual cups being of the same height there is nothing 85 to interfere with the tilting of the cup in drinking.

Having thus described my invention, what 90 I claim as new and desire to secure by Letters Patent of the United States, is:

1. A package of sanitary drinking cups, consisting of a casing and a pack of superposed collapsible cups held within the casing in folded or collapsed form, fastening means for securing the cups within the casing passing through the cups below the open ends thereof whereby the open ends of the cups will be kept closed, each cup having 95 a severing line extending transversely of the cup through the wall thereof, beyond the fastening means toward the bottom of the cup, whereby individual cups may be separated from the pack leaving the top 100 edge of the cup of uniform height and unbroken.

2. A package of sanitary drinking cups, consisting of a sheet folded to form a casing having a backing and end flaps, one 110

longer than the other, a pack of superposed collapsed paper drinking cups held within said casing with their open ends beneath the short flap, fastening means passing through the pack of cups below the open ends of the cups for securing the pack within the casing, each cup having a straight transverse line of weakness through both walls be-

yond the fastening means toward the bottom of the cup, the long flap adapted to be 10 folded over the pack of cups with its free end held beneath the short flap.

JULIUS D. TSCHOPIK.
